Des. 241,477
Patented Sept. 14, 1976

241,477

MEDICAL SUCTION INSTRUMENT

Charles A. Lahay, Fayette, Ala., assignor to Dart
Industries Inc., Los Angeles, Calif.

Filed Feb. 6, 1975, Ser. No. 547,532

Term of patent 14 years

Int. Cl. D24—02

U.S. Cl. D83—12 R

FIG. 1 is a perspective view of the medical suction instrument showing my new design;

FIG. 2 is a side elevational view thereof;

FIG. 3 is a rear view thereof;

FIG. 4 is a front view thereof;

FIG. 5 is a bottom plan view thereof;

FIG. 6 is a top plan view thereof;

FIG. 7 is a top plan view of a second embodiment of the suction instrument illustrated in FIG. 1;

FIG. 8 is a cross-sectional view taken along line 8—8 of FIG. 6; and

FIG. 9 is a cross-sectional view taken along 9—9 of FIG. 7.

The broken lines are shown for illustrative purposes only.

I claim:

The ornamental design for a medical suction instrument, substantially as shown and described.
